UNITED STATES PATENT OFFICE.

HAROLD Y. PRENDERGAST, OF BROOKLYN, NEW YORK.

SOUND-BOX.

1,338,396.

Specification of Letters Patent. Patented Apr. 27, 1920.

Application filed March 6, 1918. Serial No. 220,688.

To all whom it may concern:

Be it known that I, HAROLD Y. PRENDERGAST, a subject of the King of Great Britain, residing at Brooklyn, in the county of Kings and State of New York, have invented new and useful Improvements in Sound-Boxes, of which the following is a specification.

My invention relates to sound boxes for reproducing sounds; and its objects are to restrict the range of vibration for the diaphragm without impairing its clarity of tone, to facilitate the transference of sound to the tone arm, to improve the quality of sound reproduction, to provide a better and more effective mounting of the stylus bar, to simplify the construction of the sound box and the securing together of the several parts, and in general to reorganize and render more effective the operation of the several parts.

My invention in part consists in interposing a sounding board between the diaphragm and the tone arm of the box, the sounding board being connected with the diaphragm, held against undue vibration by yielding pressure.

My invention further consists in providing a connection for the stylus bar comprising two blades arranged in tandem, and extending in a direction parallel to the diaphragm and vibrating in unison therewith, clamps located within the wall of the sound box serving adjustably to secure the ends of the blades.

My invention further consists in various other modifications and improvements hereinafter more specifically described and claimed.

Attention is hereby directed to the accompanying drawing in which similar numerals of designation refer to similar parts throughout the several views.

Figure 1 is a view of my improved sound box from the side adjacent to the stylus bar;

Fig. 2 is a section of the box shown in Fig. 1 on line 2-2, looking in the direction of the arrows;

Fig. 3 is a view of the box from the side adjacent to the sound arm.

Referring to the drawing: The sound box 7 is constructed of metal or other suitable

material, and is preferably in the form of a short hollow cylinder. 55

Within the said box, near one end thereof, is the annular seat 8, against which rests the washer 9, in contact with the periphery of the diaphragm 10. On the opposite side of the diaphragm is the sounding board 11, 60 separated therefrom by the washer 12. The sounding board 11 is preferably slightly dished in form, the central portion thereof being at the greatest distance from the adjacent diaphragm, and is preferably constructed of wood, of the character usually employed for musical instruments, but may be made of metal or any other suitable material. From experience, I find about the best results will be obtained from silver-grained spruce, properly seasoned and varnished in the manner that the same is ordinarily prepared for use in the construction of violins and pianos or other wooden musical instruments. In the center of said 75 sounding board is the orifice 13 through which passes the sound coming from or going to the diaphragm 10, as the case may be. Between the diaphragm and the sounding board is accordingly formed the sound 80 chamber 14, which preferably gradually tapers toward the wall of the box. Through the adoption of this peculiar form of construction, I have found that the tone of the instrument is greatly improved, particularly as to quality, distinctness and accentuation, the dished or tapering construction of the sounding board serving to amplify the resonance of the sound and at the same time to mellow its tone, thereby giving 90 a very characteristic effect.

As is well known, in the reproduction of certain tones, there is grave danger that the diaphragm of ordinary construction be set in such violent vibration that such tones become shrill and rasping, the vibration being abnormally increased far beyond those necessary for the correct reproduction of the original sound. To guard against such defect, I preferably provide my sounding board with the corrugated cylindrical spring 15, one end of which rests against the washer 16 in contact with the sounding board 11 adjacent to the orifice 13, and the other end of which rests against the washer 17 in contact with the detachable cover 18, thereby 100 105

isolating the chamber 40 from the chamber 14 and passage way 13. Through such construction, in the case of too violent vibrations, the sounding board will yield against 5 the corrugated cylindrical spring 15 sufficiently to take up part of such vibrations, and adjustments can be so made as to confine the vibrations of the diaphragm within a predetermined range of vibration. Thus, 10 when notes of a high register are being reproduced, the tendency toward shrillness by reason of too rapid vibration of the diaphragm is controlled at a point within the capacity of the machine for clear tonal 15 production, without setting up the increased vibration, reproducing false tonal effects. In other words, by establishing by mechanical means a certain boundary of vibration, I am enabled to eliminate up to a certain 20 point, the tendency of the vibrations of any diaphragm to extend beyond the number of vibrations necessary to properly reproduce the sound.

Although I have found the tubular form 25 of spring 15, above described, very satisfactory and accomplishing the best results, I have also found that good results may be obtained from helical or other springs, the convolutions of which are arranged to surround 30 the passageway 13.

While, as used in my invention, the diaphragm 10 may be of mica or other suitable material, I prefer to use other material as, for example, an opaque diaphragm of material other than mica, which may be colored 35 with some distinctive color, and which is susceptible of being printed with the name of the maker, a trade mark, or embellished in some characteristic manner, a feature not 40 possessed by mica by reason of its brittleness and non-absorptive qualities.

At the center of the cover 18, and preferably integral therewith, is the wall 19 of the passageway 13 leading to the tone-arm. 45 At the edge of the cover 18 is the ring 20 through which pass the screws 21, the ends of which pass through adjacent openings in the wall of the box and engage with screw threaded openings 22 in the ring 23.

50 By using conjoint means for attaching both the covers of the box at the same time, I am enabled quickly to assemble the parts, and as quickly to take the same apart without waste of time, thereby rendering the interior of the box readily accessible. If desired, the number of screws 21 employed could be increased or diminished without rendering the construction ineffective, and other obvious changes might be made.

55 While I have described my invention with particular reference to its embodiment in the preferred form of construction above set forth, I do not desire to be understood as confining the scope of my invention to the 60 details of construction herein set forth,

since, as is obvious, various modifications and changes might be effected without departing from the spirit thereof.

What I claim and desire to secure by Letters Patent is,—

1. In a sound box, the combination of a diaphragm, a tube forming a passage-way for conveying sound therefrom, and a wooden sounding board located in spaced relation to the diaphragm and on the same 70 side thereof as the passage-way, the center of said sounding board being farthest away from said diaphragm, said sounding board intermittently vibrating during the vibration of the diaphragm.

2. In a sound box, the combination of a diaphragm, a tube forming a passage-way for conveying sounds therefrom, and a wooden sounding board located in spaced relation to said diaphragm and on the same 75 side thereof as said passage-way, the center of said sounding board being farthest away from said diaphragm, said sounding board automatically vibrating during the vibration of the diaphragm.

3. In a sound box, the combination of a diaphragm, a sounding board held in spaced relation to the diaphragm, and a cylindrical spring, said sounding board being held by said spring to yield to excessive vibrations 85 of the diaphragm.

4. In a sound box, the combination of a diaphragm, a sounding board, and a spring for holding the sounding board in operative relation to the diaphragm, said spring 100 being so tensioned that the sounding board will normally vibrate in unison with the diaphragm but will yield to dampen excessive vibrations of the diaphragm.

5. A sound box embodying a seat, a diaphragm associated with said seat, a frusto-conoidal sounding board spaced from the diaphragm, and a spring for holding the diaphragm to its seat and the sounding board in spaced relation to the diaphragm.

6. A sound box embodying a seat, a diaphragm associated therewith, a tube forming a passage-way adapted to deliver the vibratory waves from the diaphragm to a tone arm, and a frusto-conoidal sounding board spaced from the diaphragm on the passage-way side thereof and having formed therein an aperture registering with the mouth of the passage-way, in combination with a spring for maintaining the diaphragm to its seat and the sounding board in spaced relation thereto.

7. A sound box embodying a seat, a diaphragm associated therewith, a tube forming a passage-way adapted to deliver the vibratory waves from the diaphragm to a tone arm, and a frusto-conoidal sounding board spaced from the diaphragm on the passage-way side thereof and having formed therein an aperture registering with the

mouth of the passage-way, in combination with a spring positioned coaxially of the passage-way and impelling the sounding board toward the diaphragm for the purpose of holding the diaphragm to its seat and maintaining the sounding board in spaced relation thereto.

8. A sound box embodying a diaphragm, a tube forming a passage-way for conveying

sounds therefrom, and a frusto-conoidal sounding board located in spaced relation to the diaphragm on the passage-way side thereof, and adapted to be vibrated by the vibratory waves set up by the diaphragm.

In testimony whereof I have hereunto set my hand this 5th day of March, 1918.

HAROLD Y. PRENDERGAST.
